UNITED STATES PATENT OFFICE.

SCOTT HAMMOND, OF FREEPORT, ILLINOIS.

LAMP.

No. 929,423.

Specification of Letters Patent. Patented July 27, 1909.

Application filed March 17, 1909. Serial No. 483,904.

To all whom it may concern:

Be it known that I, SCOTT HAMMOND, a citizen of the United States, residing at Freeport, in the county of Stephenson and State 5 of Illinois, have invented certain new and useful Improvements in Lamps; and I do hereby declare the following to be a full, clear, and exact description of the invention, such as will enable others skilled in the art 10 to which it appertains to make and use the same.

My invention relates to new and useful improvements in lamps and more particularly to that class adapted to be used by 15 miners and my object is to provide a lamp of this kind, the body and spout of which are cast in one piece.

A further object is to cast ears adjacent the upper end of the body to which is pivotally secured the cover for the lamp and a further object is to cast a socket on the body 20 of the lamp to receive a suspension hook.

Other objects and advantages will be hereinafter referred to and more particularly 25 pointed out in the claim.

In the accompanying drawings forming part of this application, Figure 1 is a perspective view of the lamp complete. Fig. 2 is a central vertical sectional view there- 30 through, and, Fig. 3 is a transverse sectional view through the upper end of the lamp.

Referring to the drawings in which similar reference numerals designate corresponding parts throughout the several views, 1 35 indicates the body of the lamp and 2 the spout therefor, said body and spout being cast from one piece, the body being adapted to contain oil, while the spout 2 is adapted to contain any suitable form of wick (not 40 shown). A pair of ears 3 are also cast integral with the body 1 and adjacent the up-

per end thereof between which is pivotally secured a tongue 4, which tongue is integral with a cover 5, said cover having a flange 6, which is adapted to extend into the upper 45 end of the body 1 and form a perfect closure therefor. The outer face of the body 1 is also provided with an integrally cast socket 7 which is cast around the threaded end 8 of a suspension hook 9 thereby making the 50 hook 9 a fixture with the body 1 and holding the same against removal from the socket.

By constructing the lamp in this manner and casting the various parts thereof, it will 55 be readily seen that the lamp will be indestructible and will have no joints or points of leakage and it will further be seen that the lamp may be very cheaply constructed and comparatively light and will not become 60 battered and broken as is the case with lamps constructed of tin and similar metal.

What I claim is:

A device of the character described comprising a receptacle having a wick containing spout and a socket forming extension all cast integral, a closure for said receptacle having an inward extension received within the upper end of said receptacle, also in a single casting, and an attaching hook having 70 a shank initially adapted for insertion into said socket extension of said receptacle, said closure having hinged connection with said receptacle.

In testimony whereof I have signed my 75 name to this specification in the presence of two subscribing witnesses.

SCOTT HAMMOND.
